UNITED STATES PATENT OFFICE

176,771

ARROW NOCK

Theodore R. Reams, Kansas City, Mo.

Application June 8, 1951, Serial No. 15,459

Term of patent 14 years

(Cl. D34—15)

To all whom it may concern:

Be it known that I, Theodore R. Reams, a citizen of the United States, residing at Kansas City, State of Missouri, have invented a new, original, and ornamental Design for an Arrow Nock, of which the following is a specification, reference being had to the accompanying drawing, forming a part hereof.

Fig. 1 is a perspective view of an arrow nock showing my new design.

Fig. 2 is a similar view from the opposite end.

Fig. 3 is a side view.

Fig. 4 is a plan view.

Fig. 5 is a section on line 5—5 of Fig. 4.

I claim:

The ornamental design for an arrow nock, as shown.

THEODORE R. REAMS.
